HOMER D. TRACY, OF PATERSON, NEW JERSEY, ASSIGNOR TO BARBOUR FLAX SPINNING COMPANY, OF PATERSON, NEW JERSEY, A CORPORATION OF NEW JERSEY.

MACHINE FOR FORMING TUBULAR FABRICS.

1,340,425.

Specification of Letters Patent. Patented May 18, 1920.

Application filed September 27, 1919. Serial No. 326,830.

To all whom it may concern:

Be it known that I, HOMER D. TRACY, a citizen of the United States, residing at Paterson, in the county of Passaic and State 5 of New Jersey, have invented certain new and useful Improvements in Machines for Forming Tubular Fabrics, of which the following is a specification.

It is very desirable in the forming of 10 tubular material composed of intertwined strands, as the product of the braiding or circular weaving machine, to obtain uniformity of tension in the finished product, and it is the principal object of this invention to provide a machine whose product 15 will be characterized by this quality and which will be capable of turning out a greater quantity of product than ordinary machines of its class. To these ends, and 20 having reference to the improved machine in its preferred form herein set forth, the supplies for one set of strands are made to travel, spaced from each other, in a circular (non-sinuous) course, being arranged 25 so that the axes of the wound packages of 30 yarn thereof all converge to the focal or intertwining point, and the supplies of the other set of strands are arranged, stationary, beneath the first-named supplies, the latter 35 strands being moved each inward and outward across the circular path of said first-named supplies and so as to alternately pass back and forth through the successive spaces 40 between them, the instrumentalities for moving said latter strands being guided in arc-shaped paths which have the said focal or intertwining point as their center and having their guiding portions arranged also 45 to converge to said point. When the product 50 is to take the form of conventional braid, and since in the machine as so far outlined the strands which come from the lower or stationary supplies would otherwise not be spirally disposed but extend longitudinally of the finished product, I provide for 55 turning the take-up mechanism around the axis of forming such product to give said strands the desired pitch.

In the drawings,

Figure 1 is a side elevation of the improved machine, partly in section;

Fig. 2 is a plan, the superstructure being

removed and certain parts appearing in section;

Fig. 3 is a side elevation of the take-up 55 means;

Fig. 4 a view thereof mainly in vertical section; and

Fig. 5 is a plan of the hauler of said take-up means.

The bed plate *a*, supported by legs *b*, carries pairs of uprights *c d* arranged in a circle 90% apart and supporting the arc-shaped portions *e* of the circular race-forming structure in which the upper set of yarn 65 supplies travel, the ends of said portions *e* being spaced so that the race is radially slotted (between the members *c d* of each pair of uprights) as at *f*, Fig. 2. The upright *d* in each pair has a curved and slotted 70 guide *d'* whose purpose will hereinafter appear. The race has an inverted T-shaped endless slot *g*, and in this slot travel the body parts (similarly shaped) of the upper set of yarn carriers *h*, having peripheral 75 gear teeth *h'* and on each of which are arranged a spindle *i* for the yarn package *j* and a thread-guiding arm *k* pivoted to said body part of the carrier so that it may be moved away from the spindle to allow 80 clearance in fitting on or removing the yarn from the package, the several spindles converging and the guides *h'* of said guiding arms (which also have suitable yarn tension means *h''*) being adapted to be brought into 85 convergence all to substantially the same point, to wit, the yarn focal or intertwining point.

The lower yarn supplies, packages *l*, are 90 stationary, being supported in any way. The yarn from each is carried up through a guide *m* in the bed-plate *a* and then in operative engagement with a shifter, now to be described, which moves it, radially, back and forth across the circular path of the 95 upper yarn supplies. Each shifter (there are four upper and four lower yarn supplies, and hence four shifters in the present instance) consists of a slide *n* which projects through the slot *d'* of one of the uprights *d* and has a plate *n'* (Fig. 2) to retain it in the slot, *o* being a tubular thread guide projecting upwardly from the slide *n* and *p* a suitable tension device. Each slot 100

d' is concentric with the focal or intertwining point, and the guide *o* is radial with respect to the slot, so that all the guides converge toward said point in any position of 5 the slides.

The upper supplies are equally spaced from each other and in this relation travel in the race *e*, and at regular intervals (as on each upper supply having passed a slot *f*) 10 10 the yarn of the corresponding lower supply is shifted through said slot one way or the other, as the shifter is reciprocated.

The travel of the upper supplies in their race and the shifting of the yarn from the 15 lower supplies back and forth by reciprocating the shifters is accomplished thus:

In the bed-plate *a* is journaled a vertical shaft *q* in alinement with the yarn focal point, the upper end of the shaft carrying 20 20 a cam *r* formed with a bevel gear *s* and the lower end of the shaft carrying a gear *t*, the rotary structure *q*, *r*, *t* thus formed being adapted to be driven from the drive shaft *u* having a bevel pinion *v* meshing with the 25 25 bevel pinion *s*. Journaled in the bed plate *a* and the portions *e* of the race are eight vertical shafts *w* each having a pinion *x* at its lower end in mesh with the gear *t* and a pinion *y* at its upper end meshing 30 30 with the gear teeth *h'* of the yarn carriers *h*, the spacing of the pinions *y* being such as to insure each yarn carrier as it is about to clear one pinion being operatively engaged by the next in the direction of rotation. A 35 35 spider *z* having its hub *z'* fitted over the upper end of the shaft *q* and the ends *z''* of its arms forked and each receiving and secured to a pair of uprights *c* *d* is arranged over the cam *r*, and each of its arms has a longitudinal slot *z'''* which is T-shaped in cross-section (Fig. 1). Each slot forms a 40 40 radial guide for a slide *2* which is pivotally connected with the slide *n* of the corresponding shifter by a link *3*. Each slide 45 45 2 has a projection, as a roller *4*, engaged in the star-shaped slot *5* in the cam *r*, which is dished. There are four equidistant rises and falls in the camway *5*, and it being remarked that the pinions *x* and *y* are of the 50 50 same diameter, it will be apparent that on rotating the structure *q*, *r*, *t* the above described relative movements of the upper yarn supplies and the yarn from the lower supplies will be obtained.

55 It will be seen that with respect to both sets of yarn supplies intermittence of movement is entirely eliminated, the only elements which do move intermittently being the shifters for the yarn from the lower 60 60 supplies, which are parts comparatively light in weight, in consequence of which a very large part of the vibration which characterizes ordinary machines is avoided, so that the operation is attended with comparatively little noise and may proceed at 65

much greater speed than usual, with of course increased production.

Elimination of intermittence of movement of the supplies further contributes to a superior condition, in point of uniformity, 70 as to the tension of the yarn in the finished product, not only with respect to each yarn but in their relation to each other. And this is enhanced by arranging the spindles *i* of the upper supplies and the guides *h'* 75 therefor so as to converge toward the focal or intertwining point, and by arranging the shifters to move in arc-shaped paths concentric with said point, and their guides so that they also converge toward said point. 80 Among the advantages incident to moving the shifters in outwardly rising paths is the fact that in a case, like that assumed, where the yarns shifted are taken from supplies below the shifters, the angularity produced 85 in the yarn at one limit of its movement can be made the same as at the other by placing each guide *m* so that a straight line between it and the focal point will cross the path of the shifter midway between said limits 90 (compare the dotted and full lines representing the yarn in Fig. 1), thus equalizing the tension, which would of course not be possible if the shifter traveled in a horizontal plane, or perpendicular to the axis of 95 forming the product.

The focal point is afforded by a tube 6 in axial alinement with the shaft *q*. The tube is journaled in the hub of a rotary member 7 in turn journaled in an extension 8 of the 100 arm 9 of a standard 10 upstanding from the bed-plate *a*, and said tube has at its upper end a pinion 11 which meshes with the pinions 12 of two hauler devices also journaled in said member, on each side of the tube, and having grooved peripheries 13 to receive the finished product, which on issuing from the tube extends one or more times around the hauler devices before extending to the spool on which it is wound (Fig. 5); when the 105 tube is rotated the hauler devices will be rotated, thus to effect the take-up of the finished product. While the tube rotates in member 7 to cause the take-up said member is rotated, when conventionally formed 110 braid is to be the product, in the same direction as but at one-half the speed of the supplies *h*, so as to impart a pitch to the yarns coming from the supplies *l* equal to that from the supplies *h*, for otherwise it will be 115 obvious that the former yarns would be worked into the product parallel with its axis, or exactly longitudinally thereof.

The rotating of member 7 and the tube (and consequently the hauled devices) in 120 said member is effected from a pair of parallel horizontal shafts 14, 15 which are suitably journaled in standard 10 and have bevel gearing 16, 17 respectively connecting them with the lower end of the tube and 125 130

with member 7, the outer ends of said shafts being connected by gearing 18, 19 in which the member 18 is somewhat smaller than the member 19, so that although the tube and member 7 turn in the same direction the former rotates a little faster than the latter. Shafts 14 and 15 are driven from shaft *u* through a vertical shaft 20 suitably journaled in standard 10 and having spiral gear 10 connections 21, 22 with shafts *u* and 15. The gearing between shaft *u* and cam *r* and said shaft and shaft 20 is in each case 2 to 1, so that the cam and shaft 20 rotate at the same speed. The gearing between shafts 20 15 and 15 is 1 to 1, but the upper gearing 17 is 2 to 1, wherefore member 7 rotates at half the speed and in the same direction as the supplies *h* so that the yarn from the supplies *l* is given the necessary pitch.

20 The member 7 forms the base of a flier including two vertical rods 23 (either or both of which are tubular) braced at the top by a ring 24. A fixed spindle 25, whose axis is aligned with the axis of the bed plate, up- 25 stands from a cross-head 25', and on this spindle as an axis is arranged a false spindle consisting of the inner tubular member 26 having a disk-shaped lower head 26' seated upon the cross-head (there being preferably 30 an interposed anti-friction bearing 27) and an outer tubular member 28 having a slip grip connection with the member 26 and a lower head 28' provided with a coupling button 29 to engage in a suitable hole in 35 the end of the bobbin 30 on which the finished product is wound. The braid extends from one of the hauler devices up through one of the rods 23 and then to the spool, and since the flier turns and, as will appear, the 40 member 26 of the false spindle is held from turning and the spool and member 28 turn only as the friction between 26 and 28 is overcome by the pull of the braid (at slower speed than the flier) the braid will be wound 45 on the spool. The necessary traverse, to lay the finished product on the spool from end to end thereof is accomplished by providing cross-head 25' with a peripheral groove 31 to receive an interior tongue 32 50 on a ring 33 preferably made in two parts, trunnions 34 on the ring receiving the ends of a fork 35 forming the end of one arm of a bell-crank lever 36 fulcrumed in the standard 10, said arm being telescopic as indicated at 37 in Fig. 1 so as to reconcile the 55 pivotal movement of the lever to the rectilinear movement of the flier. The other arm of the bell-crank lever is engaged with a barrel cam 38 on a shaft 39 journaled in 60 standard 10 and connected by suitable worm gearing 40 with the shaft 20. There is a bail 41 whose top portion is adapted to be engaged in a notch 42 in the top of the member 26 of the false spindle, its ends 65 having slots 43 receiving the trunnions 34.

Upon loosening the milled nuts 44 on the trunnions the bail may be raised to clear the false spindle, as on doffing, the bail in its normal position holding the false spindle from turning, so that the necessary drag is imposed on the spool in order to effect the winding of the finished product thereon.

The arrangement of the upper supplies and their delivery guides and tension means so as to converge toward the focal point of 75 the yarns and of the guideways *d'* for the shifters so that the latter move in outwardly rising courses make it possible to attain the least possible throw of the shifters in order to effect the intertwining of the 80 yarns without interference with the mechanism, it being noted in this connection that tapering packages *j* are preferably utilized and that the guides *o* project well up to the bases of said packages.

The fact that the yarn controlled by the shifters is subject to tension means on and movable with the shifters instead of being placed so that the shifters move with reference to the tension means and further that 90 the shifters and hence the tension means move in constant relation to, as to distance from, the focal point of the yarns obviously contributes very considerably to the tension being practically perfectly constant at all 95 times. So far as I am aware this is new in machines of the kind set forth herein, as is also, in fact, the provision of sets of tension means, one for each set of yarns, arranged to travel so as to effect the intertwining and so that each tension means in either set will maintain a constant relation to, as to distance from, the focal point of the 100 yarns.

Having thus fully described my invention, 105 what I claim as new and desire to secure by Letters Patent is:—

1. A machine of the class set forth including, in combination, spaced devices, arranged around and substantially equidistantly from the axis of intertwining the 110 yarns, for delivering one set of yarns, means to guide the other set of yarns in a circuit around said axis and in substantially coincident alignment with said devices and the focal point of the yarns, and shifters engaging the first set of yarns between said devices and said focal point and each movable back and forth from one to the other of limits substantially equidistantly inward and outward of straight lines connecting said devices and the focal point, each outer limit being in a plane nearer than the corresponding inner limit to said focal point.

2. A machine of the class set forth including, in combination, spaced devices, arranged around and substantially equidistantly from the axis of intertwining the 120 yarns, for delivering one set of yarns, means to guide the other set of yarns in a circuit 125 130

- around said axis and in substantially conical alinement with said devices and the focal point of the yarns, and shifters engaging the first set of yarns between said devices 5 and said focal point and each movable back and forth from one to the other of limits in a curve substantially concentric with said focal point and substantially equidistantly inward and outward of straight lines connecting said devices and the focal point.
3. In a machine of the class set forth, the combination of a fixed structure having a circuitous carrier guideway and also other guideways for yarn shifters arranged at intervals and crosswise of the first guideway, spaced carriers for one set of yarns movable along the first guideway, shifters for the other set of yarns movable back and forth along the other guideways, and across the 15 first guideway, a rotary shifter actuating cam journaled concentric with the axis of intertwining the yarns, said shifter guideways being arranged relatively outward of the cam whereby the other set of yarns may be taken

from supplies beyond the cam relatively to 25 the focal point of the yarns, and transmission gearing connecting the cam and the carriers.

4. A machine of the class described including, in combination, a circuitous race 30 arranged around the axis of intertwining the yarns, spaced uprights supporting said race at intervals and having guideways extending across the race, spaced means movable along the race for conveying around 35 one set of yarns, and shifters for the other set of yarns movable in the guideways.

5. A machine of the class set forth including, in combination, a frame having means to guide one set of yarns in a circuit around 40 the axis of intertwining the yarns, reciprocating shifters for the other set of yarns, said frame having guideways for the shifters extending outward from said axis, and means to reciprocate the shifters including 45 a cam concentric with said axis.

In testimony whereof I affix my signature.
HOMER D. TRACY.
